FRAME STRUCTURE

Luther A. Blackburn, Lynwood, Calif.

Application September 16, 1946, Serial No. 697,370

3 Claims. (Cl. 189—16)

1

This invention relates to frame structures, and more specifically pertains to sectional frames for supporting and enclosing oil well pumping equipment in position for use over a well.

Oil well pumping mechanism of a type comparatively new in the field contemplates the use of a crosshead, in which the polished rod of the pump assembly is clamped, actuated by endless drive chains arranged vertically around the well. While such equipment is more costly to manufacture and install than the conventional walking beam type pumping apparatus heretofore employed, its greater efficiency dictates its use in deep wells. As there is considerable loss in the effective pumping stroke at the bottom of the well incident to elongation and contraction of the tubing string and sucker rod string which must alternately carry the load of the oil column on successive strokes of the pump, it is necessary, in order to recover a unit volume of oil, that the length of the pump stroke at the surface be proportioned to the depth of the well. The length of the stroke obtainable with the modern chain-actuated mechanism is limited only by the lengths of the chains, but as they are arranged parallel to the polished rod suitable vertical supporting structure must be provided to mount the sprockets for the drive chains as well as those required for the counterweight assembly commonly incorporated therein.

In the art prior to my invention it was common practice to build derricks of wooden or steel beams, to which plates were bolted or otherwise attached where enclosure of the structure was desired. While adequate strength is assured in frames of this type, their construction is often awkward and time-consuming, as it is usually necessary to build them on the site.

It is a principal object of the present invention to provide a frame composed of a plurality of sections adapted for facile assembly to produce a composite structure of any height desired, for the support therein of sprockets and auxiliary apparatus required for the suspension and actuation of the vertical drive chains of modern deep well pumping units.

Another and highly important object is the provision of a frame composed entirely of plate stock of novel form and arrangement to furnish accommodation for counterweight assemblies at each end thereof and to assure a maximum area within the frame for drive mechanism while contributing sufficient strength to withstand the stresses to which such apparatus is peculiarly subjected.

2

Another object is to provide a crown plate for the upper end of a vertically assembled sectional frame of the type alluded to, to afford support for bearings for counterweight chain sprockets accommodated within registering slots formed within the crown plate and adjacent end of the other upper frame section.

Still another object is to provide a frame comprising side plates adapted to perform the three-fold function of enclosing the internal pumping mechanism, of furnishing the principal support for the pump elements and actuating mechanism, and of affording vertical guides for counterweights adapted to be reciprocated with each cycle of operation of the pump.

Numerous other objects and salient features of my invention, such for example as simplicity of construction, greater facility of assembly resulting in a saving of time at the well, economy of manufacture in both materials and labor, and adaptability to pumping units of different sizes, will be apparent to those of skill in the art to which my invention appertains from an examination of the following description read in the light of the accompanying drawings, in which:

Fig. 1 is a side elevation of a two-section frame unit embodying my invention;

Fig. 2 is an end elevation of the frame shown in Fig. 1;

Fig. 3 is a horizontal section through the lower part of the unit, taken on line 3—3 of Fig. 1 and illustrating the cross-sectional contour of each section;

Fig. 4 is an exploded perspective view of the upper portion of the assembly, depicting particularly the crown plate for supporting the counter-weight sprockets and bearings;

Fig. 5 is a section taken on correspondingly-numbered lines of Fig. 1.

Referring to the drawings more in detail, the numerals of which indicate similar parts throughout the several views, 5 and 6 designate, respectively, the upper and lower sections of a two-section frame. Each section 5 and 6 comprises a pair of side plates 7, each of which comprises an intermediate vertical flat panel 8 flanked by flat-bottomed indented ribs 9. The outer sections 10 of each side plate 7 are also flat and are offset outwardly to lie in the plane of panel 8. The vertical edges of the plate are bent as indicated at 11 to form right angles with the plane of the central panel 8 and extend in the direction toward which ribs 9 are offset from the panel and outer sections 10. The angles formed

in each plate between the indented ribs 9 and panel 8 and outer sections 10 contribute the additional strength required to withstand the weight imposed thereon by the pumping unit during operation.

The side plates 7 of each section 5 and 6 of the frame are arranged in parallel, spaced relation with their respective corresponding elements directly opposed to one another, being rigidly secured in this relationship by end plates 12. End plates 12 are each formed with a central, vertical, offset rib 13 disposed intermediate the side edges to further reinforce the structure against buckling, as will appear. The end plates 12 are arranged between plates 7 in parallel planes forming right angles with the latter, the vertical edges of plates 12 being secured by welding or the like to the outer sections 10 of side plates 7 adjacent the ribs 9. To assist in maintaining this relationship, the edges 14 of end plates 12 are bent at right angles, forming narrow bearing surfaces for side plates 7. 15 indicates a plurality of triangular corner plates secured in the inside corners of the rectangle delineated by the side and end plates 7 and 12 in cross-section to reinforce the described relationship of these parts. A T-iron 16 is attached in vertical position by welding or the like to the middle of the rib 13 of each end plate 12 so as to project into the frame for guiding the ends of a crosshead (not shown), in which the polished rod of the well pump is secured, in vertical reciprocatory travel in response to actuation of the pumping unit as hereinabove generally described. It will be understood that the T-irons 16 at corresponding ends of respective sections 5 and 6 are, in any completely assembled frame, perfectly aligned to assure uninterrupted movement of the crosshead from top to bottom of the composite frame.

The inwardly-directed edges 11 of side plates 7, in addition to reinforcing the latter plates, also provide guides for counterweights adapted to reciprocate vertically in opposition to the movement of the crosshead at the outside of the respective end plates 12. Each section 5 and 6 is equipped with a pair of identical covers 17 for the ends thereof to complete the vertical enclosure in which the counterweights are raised and lowered. A plurality of hinge elements 18 are secured to the edges of each cover 17 and complementary hinge elements 19 are secured to the edges of the side plates 7 with which the covers are contiguous when the frame is assembled for use. Hinge pins 20 inserted through the respective pairs of hinge elements 18 and 19 thus secure the covers to the side plates. The removal of hinge pins 20 at one side of any one of covers 17 permits that cover to be swung outwardly on the hinge assembly at the opposite side, facilitating adjustment of the counterweights and the replacement of the cover.

While the frame sections are substantially identical in the particulars hereinabove pointed out, it will be observed by reference to Fig. 1 that each of side plates 7 of the lower section 6 is formed with a cut-out, indicated at 21, of a width at the bottom of the section substantially equal to the distance between the end plates 12. The side edges of the opening 21 in each plate converge upwardly through the ribs 9 to provide a width in opening 21 at the top thereof approximately equal to that of the panel 8.

The composite frame may be composed of sections of any number and size. The upper sections 5 are identical to one another and are se-

cured together in the same manner as are the sections 5 and 6 of the present embodiment, as is about to be described. To this end, each upper section 5 and the top of the lower section 6 are equipped with narrow flange plates 22, welded or otherwise secured to the horizontal edges of respective side plates 7 so as to project laterally therefrom. Each flange plate 22 is formed with a series of holes adapted to register with holes 10 of the plate 22 of the adjoining frame section upon assembly of the unit for the extension of bolts or the like by which the sections are releasably connected.

A crown plate 23 is superimposed upon the top of the uppermost section 5 of the assembly and conforms in outline with the upper edges of the four side and end plates 7 and 12. Each end of the crown plate 23 is accordingly formed with extensions 24 which overlie the outer sections 10 of side plates 7 to obtain additional support therefrom. A large opening 25 is formed in the center of crown plate 23 for the extension of the polished rod on the upstroke of the pumping assembly which the frame is adapted to support. The plate is slotted as at 26 at each end on a medial line, which slots 26 register with vertical slots 27 cut in the upper portions of the end plates 12 to accommodate counterweight sprockets (not shown) for the pumping unit. At 30 opposite sides of slots 26 the ends of plate 23 are bent downwardly to engage the outer surfaces of the end plates 12 at opposite sides of the vertical slots 27 so as to resist displacement of crown plate 23 in directions parallel with side plates 7. It will be understood that crown plate 23 is adapted to support bearings on opposite sides of both slots 26 for rotatable support of shafts on which the counterweight sprockets are mounted. Lateral movement of crown plate 23 relative to the sections 5 and 6 therebelow is obviated by vertical retainer plates 28 secured to the underside of crown plate 23, of a length only slightly less than the distance between the side plates 7. The retainers 28 are spaced apart a distance substantially equal to the widths of panels 8 whereby the ends thereof engage the side plates 7 adjacent the angle formed between the panels and indented ribs 9 of plates 7. The lower edges of retainers 28 are bent at right angles to contribute additional strength to the crown plate assembly.

29 indicates a cap, bolted or otherwise attached to lugs 30, mounted upon crown plate 23 to enclose the counterweight sprockets and bearings. 35 A pair of lifting eyes 31 are secured by welding or the like to the top of cap 29 to facilitate its removal and replacement when the sprocket bearings or counterweight chains require attention. Correspondingly, crown plate 32 is provided with lifting pads 32 mounted by welding or the like to each of the four corners, respectively, hereof by which plate 23 with the sprockets and bearings mounted thereon may be more easily installed in the described relationship with the frame section 5.

In order to facilitate access to the lower pumping mechanism housed within the bottom frame section 6, I provide an opening in panel 8 of one side plate 7 of said lower section 6. Along the upper edge of the opening a strip 33 is welded, one side of which overhangs the opening to receive thereunder the upper edge of a closure plate 34 of a width substantially the same as that of the opening but slightly shorter for the purpose 40 about to be described. Four lugs 35 secured to

the inner surfaces of the side plate 7, last identified, project slightly into the opening to support the closure 34 against pressure from the outside of the frame. The lower edge of closure 34 is held in place by a pair of lugs 36 attached to the outside of side plate 7 at the lower edge of the opening. The lugs 36 extend upwardly into the opening a distance less than the overhang of strip 33 at the upper edge of closure 34. A handle 37 is provided to manipulate closure plate 34 which may be placed in position to substantially fill the opening by first extending the upper edge of the closure under strip 33 and thereafter elevating the same over the lower lugs 36, behind which closure 34 may then be dropped. An opening controlled by such a closure plate may be provided in each side of the lower section, and each section thereabove may be equipped in the same manner if desired.

It will thus be noted that I have provided a frame composed of a plurality of sections adapted for most facile assembly at the point of use to provide a supporting structure of any desirable size, each section being economically constructed of plate and formed to accommodate the chains, sprockets, and crosshead mechanism of modern oil well pumping units.

While I have shown and described but one embodiment of my invention, it will be understood that many changes in size, design, shape and number of the parts may be made, that the upper section 5 of the frame and crown plate 23 may be welded or otherwise rigidly secured together prior to assembly of the composite frame at the well, that any conventional expedients may be provided to facilitate mounting the frame over the well, or the entire assembly may be supported on rails for lateral movement thereof so as to enable removal of the pumping mechanism or tubing, etc., from the well when occasion demands, and that other conventional door-supporting apparatus may be substituted for the strip 33 and lugs 35 and 36 of the present embodiment, if desired, all without departing from the spirit of my invention as defined in the appended claims.

What I claim and desire to secure by Letters Patent is:

1. In a derrick frame structure for a well pumping unit, a pair of frames, each comprising a pair of opposed side plates and a pair of opposed end plates secured rigidly in right angular relationship, said end plates being inset with respect to the lateral edges of said side plates to form a central chamber of a length less than the length of each side plate, and end chambers, each of said side plates extending at each end beyond said end plates and forming with the exterior side of each of said end plates the side walls of each one of the said end chambers each one of said end chambers being adjacent an end of said central chamber, a closure member hinged to one of said side walls of each end chamber, the upper end of one of said frames and the lower end of the other frame being flanged, means to hold said flanges of said respective frames together with one of said frames superimposed upon the other and the corresponding chambers thereof aligned with one another, and a crown plate superimposed upon the upper end of the uppermost frame having depending retainer plates extending into the central chamber of the upper frame to resist lateral displacement of the crown plate, said crown plate having a central opening therein registering with said central chamber and having elongated slots in opposite ends, respectively of said plate registering with said end chambers.

2. In a derrick frame structure for a well pumping unit, a pair of frames, each comprising a pair of opposed side plates and a pair of opposed end plates secured rigidly in right angular relationship, said end plates being inset with respect to the lateral edges of said side plates to form a central chamber of a length less than the length of each of said side plates, and vertical end chambers, each of said side plates extending at each end beyond said end plates and forming with the exterior side of each of said end plates the side walls of each one of the said vertical end chambers, each one of said end chambers being adjacent an end of said central chamber, a closure member hinged to one of said side walls of each vertical end chamber, the upper end of one of said frames and the lower end of the other frame being flanged, means to hold said flanges of said respective frames together with one of said frames superimposed upon the other and the corresponding chambers thereof aligned with one another, a crown plate superimposed upon the upper end of the uppermost frame having a central hole therein and slots in opposite ends thereof vertically aligned with the respective end chambers, means to releasably secure said crown plate on said frame, and a plurality of lifting pads secured to the corners of said crown plate.

3. In a derrick frame structure for a well pumping unit, a pair of frame sections each comprising a pair of vertical side plates and a pair of vertical end plates, the latter extending transversely between said side plates at points spaced inwardly from the ends of the latter to maintain the same in spaced parallel relationship, and form a central chamber each of said side plates having indented ribs extending vertically and disposed adjacent and between said end plates, each of said end plates having indented ribs vertically arranged and disposed equi-spaced from the lateral edges thereof, respectively, vertical guides mounted on the ribs of said end plates, respectively, and within the central chamber formed by said side and end plates, an end closure in substantially spaced parallel relation to said inwardly spaced end plates forming vertical end chambers across the spaced apart ends of said vertical side plates adjacent each end of the said central chamber, means to secure said sections together with corresponding elements thereof vertically aligned with one another, a crown plate carried on the top of the uppermost frame section, and means to maintain said frame sections and crown plate in aligned relationship.
